United States Patent Office.

WILLIAM HEARLE, OF BEAMSVILLE, CANADA, ASSIGNOR TO CHARLES L. SPENCER,
TRUSTEE, ASSIGNOR TO WILLIAM HEARLE AND ALFRED B. JOHNSON.

Letters Patent No. 97,915, dated December 14, 1869.

STOVE-PIPE DRUM.

The Schedule referred to in these Letters Patent and making part of the same.

To all whom it may concern:

Be it known that I, WILLIAM HEARLE, of the village of Beamsdale, in the township of Clinton, in the county of Lincoln, in the Province of Ontario, and Dominion of Canada, have invented a new and useful Improvement in Heating-Apparatus, or Drum-Stove; and I do hereby declare that the following is a full, clear, and exact description thereof, reference being had to the accompanying drawings, and to the letters of reference marked thereon, in which:

Figure 1 represents an elevation of the heater.

Figure 2, a view of the top and bottom of the cylinder, the caps being removed.

Figures 3 and 4 are perspective views of a plan of the upper and lower caps applicable to the heater, the same as shown in fig. 1.

Figure 5 represents the heater as used in a horizontal position.

Figures 6 and 7 are perspective views of a plan of the caps applicable to the heater, the same as shown in fig. 5.

Figure 8 is a vertical section through the centre of the drum.

My invention consists of a metal cylinder enclosing a series of air-pipes or ducts for attachment to the smoke-pipe of fuel-consuming stoves or furnaces. The smoke and heat from the latter circulate in the annular space of the cylinder, and rarefy the air in the ducts, causing it to ascend and pass into the room.

A, fig. 1, is the metal cylinder enclosing the air-ducts B. These ducts extend through the cylinder, and are held in place by heads, as shown in fig. 2, one being at each end of the cylinder, the central duct being the largest. When these ducts are heated, the air ascends through them.

A cap, C, is fitted to the bottom of the cylinder, having holes or inlets in its margin, fig. 4, through which the cold air (represented by the red arrows on fig. 1) passes into the chamber formed by the cap C, and then into the ducts.

If it be required to conduct cold air to the ducts from any given distance, the cap C should be provided with one inlet, L, fig. 1, represented by dotted lines in its side. A pipe leading from the point enters this inlet or aperture L.

To the top of cylinder is also fitted a cap, D, in which is an opening or outlet, fig. 3, to allow the heated air, represented by red arrow on fig. 1, to escape, and the rarefied air issuing therefrom may be conducted by a pipe to any particular place.

These caps, at top and bottom, also serve to check the too rapid circulation of air in the ducts, before it has become highly rarefied, by forming chamber-radiators of the two heads.

The smoke and heat (represented by black arrows)

from the fuel-stove enter the annular space of the cylinder at its side E, fig. 1, at any required distance from its bottom, and pass upward amid the ducts until they make their exit through the pipe F, in the circumference of the cylinder, near its top.

Within the cylinder, extending midway across, are two radiating-plates J, section fig. 8, encircling the ducts, and the one placed a short distance above the smoke-entrance E, the other situated on the opposite side, a little below the smoke-outlet F.

These radiating-plates prevent the direct passage of the smoke through the cylinder A, and serve to distribute the heat around the air-ducts.

In case the outlet smoke-pipe, with the radiating-plate below it, should be situated directly above the inlet smoke-pipe, it would be advisable to use a central radiating-plate, extending half way across the cylinder from the opposite side.

The contour of the cylinder may be round, oval, or any required shape, or ornamented, or plain, and the air-ducts may be of a size suitable to the circumference of the cylinder, and of any number, but much advantage will arise from the centre one being larger than the others, and the pipes proportioned to the area of the cylinder, due regard being had to the passage of the smoke.

When required to be used in position, as represented in fig. 5, the caps H and I, figs. 6 and 7, would be suitable plans to use for forming the proper circulation of air through the ducts.

The tunnel, or conical-shaped leg G, can be made a suitable height to be used with the heater, the upper end pressing into the connection K.

By the use of this invention, the cold air from the floor of the apartment is drawn off, heated, and sent upward, thus conducing to the circulation of the air and ventilation of the room.

I am aware that hot-air furnaces have heretofore been constructed, having flues and air-spaces similar to those herein described.

My invention, however, relates to the construction and arrangement of flues and air-spaces comprising a separate and distinct apparatus, attachable, at pleasure, to any ordinary heating or cooking-stove, to meet the varied requirements of the season.

I therefore claim, as my own invention—

The radiating-drum herein described, consisting essentially of the cylinder A, with smoke-inlet and exit-pipes E F, air-pipes B, perforated heads C and D, or equivalents, and deflectors J J, constructed, arranged, and operating as and for the purposes set forth.

WM. HEARLE.
